HAROLD E. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

THREAD-CARRIER-OPERATING MECHANISM FOR CIRCULAR-KNITTING MACHINES.

1,161,677.

Specification of Letters Patent. Patented Nov. 23, 1915.

Application filed June 12, 1915. Serial No. 33,666.

To all whom it may concern:

Be it known that I, HAROLD E. HOUSEMAN, a citizen of the United States, residing at Philadelphia, county of Philadelphia, and State of Pennsylvania, have invented a new and useful Improvement in Thread-Carrier-Operating Mechanism for Circular-Knitting Machines, of which the following is a full, clear, and exact description, reference being had to the accompanying drawings, which form a part of this specification.

In an application filed by Harry A. Houseman September 9, 1914, Serial No. 860,852, for thread carrier operating mechanism for circular knitting machines, there is set forth mechanism applicable to that type of machine in which the needle cylinder rotates while the cams and thread carriers are non-rotatable, whereby the thread carriers may be positively moved both into and out of operative relation with the needles. In the specific embodiment of the invention therein shown and described, the arrangement is such that any single thread may be moved into operation while any other thread carrier that has been previously rendered operative will be moved out of operation.

The object of the present invention is to modify and improve the invention of said application in such manner that any thread carrier or any plurality of thread carriers may be positively moved into action while at the same time any other thread carrier or any other plurality of thread carriers may be positively moved out of action.

In the drawings, which show a preferred embodiment of my invention: Figure 1 is a view, partly in elevation and partly sectional, of a knitting machine embodying my invention. Fig. 2 is a view of a pattern chain composed of links or cam plates forming part of the thread carrier actuating mechanism. Fig. 3 is a partial plan view of Fig. 1. Figs. 4 and 5 are sections on the lines 4-4 and 5-5 of Fig. 1. Fig. 6 is a section on the line 6-6 of Fig. 4. Fig. 7 is a diagrammatic plan view of one of the cam plates. Fig. 8 is a plan view of a modification in which the cam plates are arranged on a pattern ratchet wheel.

The rotary needle cylinder *a* may be driven by means well known in the art. Any number of thread carriers (four are shown, *d'*, *d²*, *d³*, *d⁴*) may be pivotally

mounted on a pin *c* secured to a frame *b* 55 which, as explained in Patent No. 1,127,769, dated February 9, 1915, to Houseman and Houseman, may be pivotally supported so as to be swung up to permit ready access to the needle cylinder.

The hub of each thread carrier is toothed, as at *e*, and engages the toothed hub of a lever *f*, which, together with the other three levers corresponding to the other three thread carriers, is pivoted on a pin *g* on the frame *b*. The lower ends of levers *f* (each of which is beveled) extend between the arms of the respective forked bars *h'*, *h²*, *h³* and *h⁴*, each of which has a projection *j* which normally rests upon one of a pair of pins *i*, *i*. These pins are secured, as best shown in Fig. 4 so as to span the space between the two arms of a forked bracket *k* secured to a standard *l*, which may pivotally support the frame *b*, as above explained. The arms of forked bracket *k* and the two pins *i*, *i* form a guide within which the bars *h'*, *h²*, *h³* and *h⁴* are slidable up and down. These bars are also capable of a slight swinging motion, as hereinafter explained. Gravity alone may be relied upon to cause the bars to normally drop into the position shown in Fig. 1, although other obvious means for causing them to normally assume the position may be applied if desired.

In Fig. 1 the bar *h'* is shown swung to the left of its median position. It is clear that, when moved into this position, it has swung the corresponding lever *f* in the direction to move down the yarn carrier *d'* into operative position. It is also clear that if the bar *h'* is swung to the right of its median position, it will swing the corresponding lever *f* in the direction to move the yarn carrier *d'* up out of operative position. To so swing the yarn carriers I have provided bell crank levers *m* and *n* pivoted on brackets *q* secured to standard *l*. The levers *m* and *n* are pivoted on opposite sides 95 of the set of bars. Lever *m*, at one free end, carries a finger *o* which is in operative relation with a projection *r* on each bar when the latter is in its lower position, as shown in Fig. 1; and lever *n*, at its free end, carries 100 a finger *p* which is in operative relation with a projection *s* on each bar when the latter is in its raised position. Thus it will

be understood that if any given bar be in its lowered position and if lever *m* is then actuated, the corresponding thread carrier, if in operative position, will be lifted out of operative position while the actuation of lever *n* will have no effect upon such bar and thread carrier; whereas if any given bar be in its raised position and if lever *n* be then actuated, the corresponding thread carrier, if in operative position, will be moved down into operative position while the actuation of lever *m* will have no effect upon such bar and thread carrier. It will thus be seen that if selective or pattern controlled means are provided to lift any one or more bars corresponding to the thread carriers that it is desired to render active and if both levers *m* and *n* be then actuated, the result will be to move such thread carrier or carriers into action while the remaining thread carrier or carriers will, if in operative position, be rendered inoperative. Again, if, prior to the actuation of levers *m* and *n*, it is desired to maintain any thread carrier in operative position, then if its corresponding bar be lifted, neither of levers *m* and *n* will swing the bar, and the thread carrier will remain in operative position; while if it is desired to maintain any thread carrier in inactive position, then if its corresponding bar be not lifted, neither of levers *m* and *n* will swing the bar, and the thread carrier will remain in inactive position. Thus it will be understood that, prior to the actuation of levers *m* and *n*, any inactive thread carrier or carriers may be rendered active and any active carrier or carriers may be caused to remain active by lifting the corresponding bar or bars, while the other bar or bars are not lifted.

To effect the lifting of bars *h'*, *h²*, *h³*, and *h⁴* and the actuation of levers *m* and *n* I have provided cam plates *t*. Each cam plate carries a cam *u* and a cam *v*. Cam *u*, through a spring pressed rod *w*, actuates lever *m* (which, as before explained, effects the lifting of the thread carriers out of action). Cam *v*, through a spring pressed rod *x*, actuates lever *n* (which, as before explained, effects the depression of the thread carriers into action). Each cam plate also carries one or more selector cams *y*, which act to lift bars *h'*, *h²*, *h³* and *h⁴*. Each bar is provided at its lower end with a projection *z*. The four projections of the four bars are arranged out of alignment one with the other so that when cam plate *t* underlies the bars, any one or more of the bars will be lifted dependent upon the number and position of cams *y*. Thus, in Fig. 7, the cam plate is shown as provided with one cam *y* which is in line with the projection *z* on (say) bar *h³*. As the cam plate passes under the bars it lifts bar *h³* while all the other bars remain down. The result will be that,

after the actuation of levers *m* and *n*, whatever the preceding positions of the several thread carriers may be, thread carrier *h³* will be in its lower or operative position while the remaining thread carriers will be in their upper or inoperative positions.

The relative positions of rods *w* and *x*, projections *z* and cams *u*, *v* and *y* are such that as cam plate *t* travels under said rods and projections the bar or bars to be lifted will be first actuated. Then cam *v* lifts rod *x*, actuating lever *n*, which actuates any lifted bar or bars to cause the corresponding carrier or carriers to be moved down into operative position. Then cam *u* lifts rod *w*, actuating lever *m*, which actuates the remaining bar or bars to cause the corresponding carrier or carriers to be moved up out of operative position. The successive, instead of absolutely simultaneous, movements of levers *n* and *m* are preferred, to insure the placing of new thread in the needles before the old thread is removed therefrom.

Cam plates *t* may be brought successively into operative relation with the thread carrier actuating devices at intervals governed by the pattern mechanism or may themselves be part of the pattern mechanism. Thus in Fig. 2 I have shown the cam plates as alternate links of a chain 12 driven by a wheel 10, which may itself be a pattern wheel or may be turned at intervals by separate pattern mechanism. In Fig. 8 I have shown the cam plates mounted on a wheel 11 having ratchet teeth by which it is turned at intervals. Such a pattern ratchet wheel is set forth in the Houseman and Houseman Patent No. 1,127,768, dated February 9, 1915.

To hold a thread carrier in the position up or down—to which it has been moved, I provide a spring actuated pawl lever 13 pivoted on frame *b* and adapted to engage either one of two detents in the hub of the carrier lever dependent upon whether the carrier is swung up or down.

It will be noted that the ends of the two forked arms of each carrier-actuating bar are beveled outwardly toward their ends. If the frame *b* is swung up on its pivot, as before explained, levers *f* will be carried out of the mouths of the forked ends of the bars. The beveled faces of these forked arms facilitate proper reengagement of levers and bars when the frame *b* is returned to its normal position.

It will be understood that when a thread carrier is raised into inoperative position and thus out of the range of the revolving needles, some customary means will be provided to sever the threads.

Having now fully described my invention, what I claim and desire to protect by Letters Patent is:

1. In a circular knitting machine, the com-

- bination of a rotatable needle cylinder, a plurality of non-rotatable independent thread carriers each of which is adapted to feed thread to the needles of said cylinder, and positively operated mechanism adapted to positively move any one of said carriers, or a plurality of said carriers simultaneously, into or out of action. 5
2. In a circular knitting machine, the combination of a rotatable needle cylinder, a plurality of non-rotatable independent thread carriers, and positively and independently operable devices, one for each carrier, and each adapted to positively move its corresponding carrier both into and out of action. 10
3. In a circular knitting machine, the combination of a rotatable needle cylinder, a plurality of non-rotatable independent thread carriers, and positively operated mechanism to successively positively move one or more carriers into action and one or more carriers out of action. 20
4. In a circular knitting machine, the combination of a rotatable needle cylinder, a series of non-rotatable independent thread carriers adapted to be moved into and out of action, and pattern controlled mechanism adapted to be operated to first dictate the movement of any one or more carriers in either direction and then positively operate the same. 25
5. In a circular knitting machine, the combination of a needle cylinder, a plurality of independent thread carriers, independent actuating devices for the respective thread carriers each of which is adapted to positively move its corresponding thread carrier both into and out of action, and positively operating means adapted to selectively control said devices and positively actuate them to effect the shift of their respective thread carriers. 35
6. In a circular knitting machine, the combination of a needle cylinder, a plurality of independent thread carriers, independent actuating means for the respective carriers each of which is adapted to positively carry both into and out of action, and mechanism adapted to first position and then positively operate said carrier actuating means. 45
7. In a circular knitting machine, the combination of a needle cylinder, a plurality of independent thread carriers, devices adapted to be moved in opposite directions and thereby positively move their respective carriers into or out of action, and cam mechanism adapted to first position a plurality of said devices for movement in opposite directions 55 and then positively operate the same. 60
8. In a circular knitting machine, the combination of a rotatable needle cylinder, a series of non-rotatable independent thread carriers, positively operated mechanism adapted to positively move all said carriers simultaneously into or out of action, and pattern controlled means to selectively control the operation of said carriers by said mechanism. 65
9. In a circular knitting machine, the combination of a needle cylinder, a series of independent thread carriers, positively and independently operable devices, one for each carrier, and each adapted to positively move its corresponding carrier both into and out of action, positively operated mechanism respectively adapted to positively actuate said devices in opposite directions and thereby move the corresponding carriers into or out of action, and pattern mechanism adapted to selectively control the operations of said devices by said mechanism. 70
10. In a circular knitting machine, the combination of a rotatable needle cylinder, a plurality of non-rotatable independent thread carriers, and positively operated means separate from but operatively connected with the thread carriers for successively positively moving one or more thread carriers into action and one or more thread carriers out of action. 75
11. In a circular knitting machine, the combination of a rotatable needle cylinder, a plurality of non-rotatable independent thread carriers, positively operated mechanism to move said thread carriers into action, positively operated mechanism to move said thread carriers out of action, and means to bring any one or more thread carriers into simultaneous operative relation with either of said mechanisms. 80
12. In a circular knitting machine, the combination of a rotatable needle cylinder, a plurality of non-rotatable independent thread carriers, positively operated mechanism to move said thread carriers into action, positively operated mechanism to move said thread carriers out of action, and means to bring any two carriers successively into operative relation one with one mechanism and the other with the other mechanism. 85
13. In a circular knitting machine, the combination of a needle cylinder, a plurality of independent thread carriers, independent actuating devices for the respective thread carriers each of which is adapted to move in opposite directions and thereby positively move its corresponding thread carrier into or out of action, positively operating means adapted to positively actuate said devices in both directions, and pattern mechanism adapted to selectively control the operation of said means. 90
14. In a circular knitting machine, the combination of a needle cylinder, a plurality of independent thread carriers, independent actuating devices for the respective thread carriers each of which is adapted to move in opposite directions and thereby positively 100

move its corresponding thread carrier into or out of action, mechanism to positively move said devices in one direction, mechanism to positively move said devices in the 5 opposite direction, and selecting means to bring different combinations of said devices into operative relation with said mechanisms.

15. In a circular knitting machine, the 10 combination of a needle cylinder, a plurality of independent thread carriers, positively operated mechanism adapted to simultaneously move all the carriers out of action, positively operated mechanism to return the 15 carriers into action, and selective means to render the first mechanism inoperative to move any one or more carriers.

16. In a circular knitting machine, the combination of a needle cylinder, a plurality 20 of independent thread carriers, positively operated mechanism adapted to simultaneously move all the carriers into action, positively operated mechanism to withdraw the carriers from action, and selective means to 25 bring the first mechanism and any one or more of said carriers into operative relation.

17. In a circular knitting machine, the combination of a needle cylinder, a plurality 30 of independent thread carriers, independent devices adapted to positively move the respective carriers both into and out of action, mechanism adapted to positively actuate any of said devices to cause it, dependent upon its position, to move its corresponding thread carrier either into or out of action, and means to independently position said devices.

18. In a circular knitting machine, the 40 combination of a needle cylinder, a plurality of independent thread carriers, independent devices adapted to positively move the respective carriers both into and out of action, mechanism adapted, when said devices are in one position, to positively move their corresponding thread carriers into action, mechanism adapted, when said devices are in another position, to positively move their corresponding thread carriers out of 45 action, and means to independently control the positions of the several devices.

19. In a circular knitting machine, the combination of a needle cylinder, a plurality 55 of independent thread carriers, independent devices adapted to positively move the respective carriers both into and out of action, mechanism adapted, when said devices are in one position, to positively move their corresponding thread carriers into action, mechanism adapted, when said devices are in another position, to positively move their corresponding thread carriers out of 60 action, and means to first position said devices and then successively actuate the two mechanisms.

20. In a circular knitting machine, the combination of a needle cylinder, a plurality of independent thread carriers, devices adapted, according to their positions, to independently move their respective 70 thread carriers into or out of action, and a succession of periodically actuated sets of cams, each set comprising a selective cam or cams adapted to determine the positions of said devices, a carrier lifting cam adapted to 75 actuate any device in one position and a carrier depressing cam adapted to actuate any device in the other position.

21. In a circular knitting machine, the combination of a needle cylinder, a plurality 80 of independent thread carriers, carrier depressing mechanism, carrier lifting mechanism, and a succession of periodically actuated sets of cams, each set comprising a carrier depressing cam adapted to actuate the 85 first mechanism, a carrier lifting cam adapted to actuate the second mechanism, and a selective cam or cams adapted to control the actuation by said mechanisms of the several thread carriers.

22. In a circular knitting machine, the combination of a needle cylinder, a plurality of independent thread carriers, independent bars adapted, dependent upon their positions, to be actuated to move their corresponding carriers either into or out of action, a lever adapted to actuate any bar occupying one position, and a lever adapted to 95 actuate any bar occupying another position, whereby the positions of all the thread carriers may be determined, in advance of the 100 operation of said levers, by controlling the positions of the corresponding bars.

23. In a circular knitting machine, the combination of a needle cylinder, a plurality 105 of independent thread carriers, independent bars adapted, dependent upon their positions, to be actuated to move their corresponding carriers either into or out of action, a lever adapted to actuate any bar occupying one position, a lever adapted to 110 actuate any bar occupying another position, and selective means to independently control the positions of the several bars.

24. In a circular knitting machine, the 115 combination of a needle cylinder, a plurality of independent thread carriers, independent bars adapted to be moved to move the respective thread carriers both into and out of operative position, a carrier depressing lever 120 and a carrier lifting lever adapted to so move said bars, and pattern mechanism adapted to render either lever inoperative to actuate any of said bars.

25. In a circular knitting machine, the 125 combination of a needle cylinder, a plurality of independent thread carriers, independent bars adapted to be moved to move the respective thread carriers both into and out of operative position, a carrier depressing 130

- lever and a carrier lifting lever adapted to so move said bars, traveling set of cams two of which control the operation of the respective levers and one or more of which control 5 the positions of said bars to bring each bar into operative relation with one or the other lever.
26. In a circular knitting machine, the combination of a needle cylinder, a plurality 10 of independent thread carriers, independent bars adapted to be moved to move the respective thread carriers both into and out of action, carrier-depressing and carrier-lift- 15 ing levers adapted to so move said bars, rods 18 adapted to actuate the respective levers, a cam or cams adapted to control the positions of said bars to bring each bar into operative relation with one or the other lever, and cams adapted to successively actuate the 20 respective rods.
27. In a circular knitting machine, the combination of a needle cylinder, a plurality 25 of individual thread carriers, bars slidable longitudinally relatively to the thread carriers and also swingable in opposite directions to positively move the respective thread carriers into and out of action, mechanism to swing the bars in one direction or the other dependent upon the longitudinal positions 30 of the bars, and means controlling the longitudinal position of each bar.
28. In a circular knitting machine, the combination of a needle cylinder, a plurality 35 of individual thread carriers, bars slidable longitudinally relatively to the thread carriers and also swingable in opposite directions to positively move the respective thread carriers into and out of action, mechanism to swing the bars in one direction or the 40 other dependent upon the longitudinal positions of the bars, and traveling cams adapted to control the longitudinal position of each bar and actuate said mechanism.
29. In a circular knitting machine, the 45 combination of a needle cylinder, a plurality of individual thread carriers, independent bars slidable longitudinally relatively to the thread carriers and also swingable in opposite directions to positively move the respective thread carriers into and out of action, means controlling the longitudinal position of each bar, and a carrier lifting lever and a carrier depressing lever one or 50 the other of which is adapted to actuate each bar dependent upon the latter's longitudinal position.
30. In a circular knitting machine, the 55 combination of a needle cylinder, a plurality of individual thread carriers, independent bars slidable longitudinally relatively to the thread carriers and also swingable in opposite directions to positively move the respective thread carriers into and out of action, a carrier lifting lever, a carrier de- 60 pressing lever one or the other of which is
- adapted to actuate each bar dependent upon the latter's longitudinal position, and traveling cams two of which are adapted to operate the respective levers and the remainder of which are adapted to control the position 70 of each bar.
31. In a circular knitting machine, the combination of a needle cylinder, a plurality 75 of individual thread carriers, levers geared to the respective carriers, bars slidable longitudinally relatively to said levers and also swingable in opposite directions to swing the respective lever and thereby positively swing the respective thread carriers into and out of action, mechanism to swing the bars 80 in one direction or the other dependent upon the longitudinal positions of the bars, and means controlling the longitudinal position of each bar.
32. In a circular knitting machine, the 85 combination of a needle cylinder, a plurality of individual thread carriers, bars slid- 90 able longitudinally relatively to the thread carriers and also swingable in opposite directions to positively move the respective carriers into and out of action, projections on opposite edges of each bar, levers one adapted to engage the set of projections on one side and the other adapted to engage the set of projections on the other side, and means to control the longitudinal position of each bar to bring it into operative relation 95 with one or the other lever.
33. In a circular knitting machine, the 100 combination of a needle cylinder, a plurality of individual thread carriers, levers geared to the respective carriers, forked bars, each lever extending between the forked arms of its corresponding bar, means to independently slide the bars, and mechanism to swing each bar in one direction or 105 the other dependent upon its longitudinal position.
34. In a circular knitting machine, the 110 combination of a needle cylinder, a plurality of individual thread carriers, levers geared to the respective carriers, a pivoted frame on which said carriers and levers are swiv- 115 eled, bars one for each lever, each bar having forked arms beveled at their outer ends and between which the corresponding lever enters when said frame is swung into operative position, mechanism to swing the bars in opposite directions, and means controlling the direction in which each bar is swingable. 120
35. In a circular knitting machine, the 125 combination of a needle cylinder, a plurality of independent thread carriers, independent actuating devices for the respective carriers each of which is adapted to positively move its corresponding carrier both into and out of action, mechanism adapted to positively actuate said devices to effect the movement into action of their respective carriers, other mechanism adapted to posi- 130

tively actuate said devices to effect the movement out of action of their respective carriers, each of said devices being independently movable relatively to said mechanisms 5 to bring it into operative relation with one or the other of said mechanisms.

36. In a circular knitting machine, the combination of a rotatable needle cylinder, a series of non-rotatable independent thread carriers adapted to be moved into and out of action, two oppositely-acting and positively actuated mechanisms, and pattern-

controlled intermediate devices, one for each carrier, each of which is adapted to be independently positioned to bring its corresponding carrier into operative relation with one or the other of said mechanisms to enable the latter to positively move such carrier into or out of action. 15

In testimony of which invention, I have 20 hereunto set my hand, at Philadelphia, on this 9th day of June, 1915.

HAROLD E. HOUSEMAN.
